United States Patent Office

Des. 196,637
Patented Oct. 22, 1963

196,637

SHELTER

Victor F. Christ-Janer, Frogtown Road,
New Canaan, Conn.

Filed Dec. 13, 1962, Ser. No. 72,844

Term of patent 14 years

(Cl. D13—1)

FIG. 1

FIG. 2

I claim:

The ornamental design for a shelter, as shown and described.
